WATER FOUNTAIN

John O. Hruby, Jr., Burbank, Calif., assignor to Rain
Jet Corporation, Burbank, Calif.

Filed June 1, 1970, Ser. No. 23,209

Term of patent 14 years

Int. Cl. D23—01

U.S. Cl. D23—13

FIG. 1.

FIG. 2.

FIG. 3.

FIG. 1 is a perspective view of a water fountain showing my new design.

FIG. 2 is a cut away perspective view thereof.

FIG. 3 is a partial plan view thereof.

The broken line representation of a discharge head in FIGS. 1 and 2 is for the purpose of illustration only.

I claim:

The ornamental design for a water fountain, as shown and described.
